United States Patent Office

Des. 181,709
Patented Dec. 17, 1957

181,709

OUTBOARD MOTOR BOAT OR SIMILAR ARTICLE

Meade Bly Davidson, Dallas, Tex.

Application November 19, 1956, Serial No. 43,839

Term of patent 14 years

(Cl. D71—1)

I claim:

The ornamental design for an outboard motor boat or similar article, substantially as shown.
